UNIDIRECTIONAL BREATHER

Filed May 14, 1931

UNITED STATES PATENT OFFICE

2,000,862

UNIDIRECTIONAL BREATHER

Louis C. Nichols, Wauwatosa, Wis., assignor to
 Allis-Chalmers Manufacturing Company, Milwaukee, Wis., a corporation of Delaware

Application May 14, 1931, Serial No. 537,303

15 Claims. (CL 220—85)

This invention relates to breathers for transformers, oil circuit breakers, and the like.

Electrical apparatus of this type usually have either a main or an auxiliary tank which is partially filled with oil, leaving an air space in the tank above the oil. The air in this space above the oil is ordinarily in communication with the outside air by means of an opening in the top of the tank commonly called a "breather" because it permits the tank to breathe air in or out as the oil contracts and expands due to temperature changes. Since the apparatus usually breathes in and out through the same opening there is practically no circulation of air within the tank. The air in the tank above the oil is heated by the warm oil and therefore readily absorbs moisture from the air coming in through the breather and also from the oil, and since there is substantially no circulation of this air, the moisture content increases. When the conditions are such that the metal top of the tank cools the moisture laden air in the space above the oil to a temperature below the dew-point of the air, moisture will condense on the inner surfaces of the tank cover or top. This moisture accumulates and causes rusting, and dripping of water and rust into the oil and onto the electrical parts below with the resulting danger of the insulation breaking down and causing destructive arcing.

An object of this invention is to minimize the danger of insulation breakdown and rusting of metal parts in transformers, oil circuit breakers, and the like due to the moisture in the air therein.

Another object of this invention is to prevent the condensation of the moisture in the air in the space above the insulating liquid in transformers, oil circuit breakers, and the like.

Another object of this invention is to provide a container partially filled with oil or similar liquid that is subjected to temperature changes with a "breather" means which will prevent condensation of moisture in the space above the liquid.

Another object of this invention is to attain the above objects by utilizing heat from the insulating liquid to induce uni-directional flow of fresh air through the space above the level of the insulating liquid.

A further object is to provide a device which can be cheaply manufactured and readily installed inside or outside oil immersed electrical apparatus to carry warm air into the casing of such apparatus and out through the usual breather pipe.

These and other objects and advantages are attained by this invention, various novel features

of which will be apparent from the description and drawing herein, and will be more particularly pointed out in the claims.

Various illustrative examples of the application of this invention are shown in the accompanying drawing in which:

Fig. 1 is a view partly in section of a transformer having an expansion tank embodying the invention.

Fig. 2 is a sectional view of a conventional single tank transformer embodying the invention.

Fig. 3 is a sectional view of a conventional transformer embodying a modified form of the invention.

Fig. 4 is sectional view along the line IV—IV of Fig. 3.

Fig. 5 is partial section view of an oil circuit breaker embodying the invention.

Fig. 6 is a side view of a transformer similar to Fig. 1 showing the expansion tank in section and including the invention.

Referring now in more detail to the drawing, in Fig. 1, 8 designates the main tank of a transformer which has a cover 10. The expansion or "conservator" tank 11 is supported from the main tank by means of brackets 12—12. An oil conduit 14 connects the expansion tank 11 with the main tank 8 and forms a conduit for the passage of oil 15 to and from these tanks. A gauge 16 is provided to indicate the height of the oil in the tank 11. A ventilating intake conduit 17 extends from outside the expansion tank 11 upwardly through the bottom of tank 11 at one end thereof and through the oil 15 to a point near the top of the tank. The air conduit 17 is attached to the tank 11 by welding or by any suitable pipe connection.

A chamber 18 containing a deoxidizing agent may be attached to the intake conduit 17. A screen 19 is attached to the inlet end of pipe 17 and serves to prevent the admission of foreign matter into the intake pipe.

An outlet conduit 20 is connected to the top of the tank 11 near the end opposite to the intake and serves as a conduit for carrying air from inside the tank 11 to the outside air. The outlet conduit 20 is unobstructed by check valves or the like but it does preferably contain a screen as does the inlet conduit to keep out foreign matter.

Obviously this outlet 20 may take the form of any of the known "breathers", it being understood, however, that in apparatus 50 constructed in accordance with this invention, the circulation of air through the breather will be uni-directional instead of in and out as heretofore.

The operation of Fig. 1 is as follows:—When

the oil surrounding air conduit 17 is warmer than the outside air, the column of air within conduit 17 will be warmed by the oil 15 and will therefore become lighter, and will have the tendency to rise 5 thereby causing fresh air to be drawn through screen 19 and discharge into the upper part of tank 11. This intake of fresh air will cause a displacement of the air above oil 15 and consequent sweeping out of air throughout the space above 10 the oil and out the outlet conduit 20. The air coming into the tank 11 being warmer than the outside air will readily absorb moisture from the walls of tank 11 and from the oil 15 and will discharge this moisture laden air through conduit 15 20. It will thus be seen that the moisture content of the oil 15 will be reduced and that rusting of the metal top of tank 15 will be prevented; also the dielectric strength of good oil will be maintained at a high value and the dielectric strength 20 of oil containing moisture will be gradually improved. In some installations it may be desirable to remove the oxygen from the air entering the inlet of pipe 17 to prevent sludging of the oil within the tank, and this is accomplished by the 25 action of suitable chemicals within container 18 through which the intake air passes. If this action is not desired, chamber 18 may be removed and the screen 19 attached directly to conduit 17. The tank 11 has been shown and described as an 30 expansion tank for a transformer, however, the invention may be applied in a similar manner in conjunction with any container for oil or similar material that is subjected to changes in temperature, for example, an oil storage tank subjected 35 to atmospheric temperature changes.

In Fig. 2 a transformer of the single tank type is shown. The tank or casing 21 is provided with a top member 23. The core and windings are designated generally by 22. The usual conductors 40 are led through bushings 24 and 25 to the transformer windings. A conduit 26 extends through the tank 21 near the bottom thereof, vertically upward within the transformer to a point above the level of oil 15 and constitutes an air inlet 45 conduit. This conduit 26 is attached at its lower end to the tank 21 either by welding or by any suitable connecting means, and at its upper end by a guide member or bracket 28 which is welded or otherwise fastened to the tank 21. The conduit 26 is shown as bent at its lower end, but it will be understood that suitable pipe fittings can be used instead. A screen 19 is provided for the inlet pipe 26 and the oxidizing element 18 (shown in Fig. 1) may be interposed in the inlet conduit 50 if so desired. An outlet conduit 20 is attached to the upper part of top 23 and serves to exhaust the air drawn in by the action of conduit 26. In some instances, sufficient draft through conduit 26 may be secured by placing the inlet connections at 55 a higher point in casing 21 or it may be extended through the bottom of the tank as shown in Fig. 5. The operation of this figure is the same as that described in connection with Fig. 1.

In Figs. 3 and 4 a transformer of conventional type having corrugated side walls 31 is shown. 60 To the upper cylindrical portion 32 of this transformer is attached by welding or other connecting means an intake conduit 34 which extends vertically downward, between adjacent corrugations 70 31. A detachable element 37 carrying screen 38 is provided in the intake of the inlet end of conduit 34, and the upper end of this conduit is in communication with the inside of the transformer at a point above the level of oil 15. An outlet conduit 26 75 is provided in the cover member 33 of the

transformer. The radiation of heat from corrugations 31 is usually sufficient to induce circulation of air through conduit 34 through the space above oil 15 and out outlet 20, but should it be desired to increase this circulation, heat conductive material 36, such as copper-wool, may be packed around inlet conduit 34 between corrugations 31 and retained in place if necessary by a sheet metal member 35 welded or otherwise attached to the corrugations 31. The lower end of conduit 34 is attached to the side walls 31 of the casing by means of element 35 or by means of a guide bracket such as shown at 28 in Fig. 2.

In Fig. 5 the invention is shown as applied to a conventional type oil circuit breaker having 15 casing 40, guard member 41, movable switch blade 42 and stationary switch clips 43 supported by insulator 44. The switch 42 is operated by operating rod 45 through mechanism (not shown) in the switch housing 46. An intake conduit 47 extends vertically through the bottom of casing 14 through oil 15 to the air space above the oil 15 and is attached to the casing at the bottom by welding or other connecting means and near the top by the supporting member or bracket 49 which 20 is welded or otherwise fastened to tank 40. A screen 48 covers the inlet opening of conduit 47 and serves to keep out foreign matter. The air which is drawn into the space above the oil circulates through openings 50 around the operating rod 45 into the chamber 46 housing the switch mechanism and finally out the outlet conduit 51. It is evident that the successive operations of 25 the oil circuit breaker will heat up the oil and cause the ventilating air to circulate in the manner described in connection with Fig. 1.

Fig. 6 illustrates an application of the invention to a transformer having an expansion tank of the type shown in Patent No. 1,793,820, granted to L. C. Nichols on February 24, 1931. The main 40 tank 9 supports the expansion tank 11 by means of the oil conduit 52 which is welded or otherwise fastened to tanks 10 and 11. The intake and outlet conduits 17 and 20 are shown as provided with screens 19 and 19' respectively. The oil 45 conduit 52 extends through the expansion tank and is covered by a hinged relief valve 53 which upon occurrence of abnormally high pressures 50 opens to relieve the internal pressure. The embodiment of the invention shown in this figure operates the same as described in connection with Fig. 1.

For the purposes of explanation of the specific embodiments shown herein, reference has been made to the outlet conduit member as being in 55 the "top" of the casing. The term "top" as used in this connection is intended to include any wall portion of the casing above the level of the liquid contained in the vessel. Also the medium above the level of the oil and in the inlet and outlet 60 members has been referred to as "air", however, it is readily apparent that the invention is applicable in a like manner with any gaseous medium similarly used.

It is thus evident that the above devices provide means for utilizing the heat from the insulating oil of transformers and oil circuit breakers to cause a uni-directional circulation of air or inert gas through the space above the oil 65 6, and show that this invention may be practiced 70 by using an air intake conduit mounted either inside or outside the apparatus. It is to be understood that the devices above described are merely illustrative of the invention for it will be apparent that various changes in the arrangement 75

and proportion of parts may be made within the scope of the invention as defined in the appended claims.

It is claimed and desired to secure by Letters Patent:—

5. 1. In combination, a casing for electrical apparatus, said casing containing a quantity of liquid at a higher temperature than the atmosphere and having an air space above the level of said liquid, said casing having an air vent above the level of said liquid, an air inlet conduit having an air inlet opening located below the level of said liquid and in communication with atmosphere, said inlet conduit extending parallel to said casing for substantially the same distance as the depth of the liquid within said casing, and means for securing said inlet conduit to said casing in heat conductive relation to said hot liquid so that heated air within said conduit induces a uni-directional circulation of heated air through said air space and out through said vent whereby moisture within said air space is removed by said heated air.

2. In combination, a fluid container, a quantity of liquid at a higher temperature than the atmosphere partially filling said container so as to leave an air space above the level of said liquid, an air outlet affording unrestricted communication between said air space and atmosphere, an air inlet conduit having an inlet opening located below the level of said liquid and affording unrestricted communication between said air space and atmosphere, and means for holding said inlet conduit to said casing in heat conductive relation to said liquid so that moisture within said air space is carried out through said outlet by a uni-directional movement of heated air through said air space.

3. The combination with a main casing for electrical apparatus, of an auxiliary casing, insulating liquid filling said casing and partially filling said auxiliary casing, a conduit between said main casing and said auxiliary casing providing a passageway for said liquid, an air outlet conduit in said auxiliary casing, and an air inlet conduit in said auxiliary casing extending from a point about the level of said liquid spaced from said air outlet through said liquid and through said auxiliary casing to the outside air near the bottom of said auxiliary casing.

4. In combination, a casing for electrical apparatus, a quantity of insulating liquid partially filling said casing, an air outlet conduit in the top of said casing, an air intake conduit extending from above the level of said liquid through said liquid and through said casing to the outside air near the bottom of said casing.

5. In combination, a casing for electrical apparatus, said casing having corrugations in the sides thereof, a quantity of insulating liquid partially filling said casing, an air conduit extending upward between adjacent corrugations of said casing and into said casing above the level of said liquid, means for transferring heat from said liquid to said conduit, and a second conduit mounted in the top of said casing above the level of said liquid.

6. In combination, a casing for electrical apparatus, a quantity of liquid partially filling said casing and normally subjected to heating, an unrestricted air vent mounted on said casing above the level of said liquid, and an inlet air conduit extending through said casing near the bottom thereof and through said liquid for substantially

the full depth thereof thereby providing an unrestricted path for the flow of air into said casing in response to the heating of the air in said inlet conduit by said liquid.

7. In a liquid containing tank having an air space above the level of said liquid, the combination of a vent member for carrying air from said air space to atmosphere, and means for increasing the moisture absorbing ability of the air flowing through said air space comprising an air inlet conduit supported by said casing in heat conductive relation to said liquid and providing an unrestricted path for the flow of heated air into said air space.

8. In combination, a casing, a quantity of liquid partially filling said casing so as to leave an air space in said casing above said liquid, said liquid normally having a temperature higher than the atmosphere adjacent said tank, an outlet vent providing unrestricted communication between said air space and atmosphere, and an unrestricted air inlet conduit arranged in intimate heat transferring relation to said liquid and providing a permanently free passageway from atmosphere to said air space through said inlet conduit, whereby the heated air flowing from said inlet conduit is capable of absorbing moisture within said air space.

9. In a casing having a quantity of liquid therein and an air space above said liquid, an outlet vent mounted on said casing so as to provide a continuously unrestricted passage for the flow of air from said space to atmosphere, an inlet conduit so mounted on said casing in heat conductive relation to said liquid as to provide a continuously unrestricted path for the flow of air from atmosphere into said space at a point removed from said outlet vent so that the air in said inlet conduit is warmed by said liquid and is thereby caused to absorb and carry moisture from said air space through said outlet vent to atmosphere.

10. In a tank having a quantity of liquid therein and an air space above said liquid, the combination of an outlet member so mounted on said tank as to provide a path for the flow of air from said air space to atmosphere, means providing a path for the uni-directional and continual flow of air from atmosphere into said air space at a temperature higher than the temperature of the atmosphere comprising an inlet member mounted on said tank in heat conductive relation to said liquid.

11. In combination, a tank for oil immersed electrical apparatus, a body of oil in said tank for dissipating the heat from said electrical apparatus to said tank, said tank having an air space therein above the level of said oil, means providing a permanently free path for the flow of air from said air space to atmosphere, means for producing a uni-directional flow of heated air through said air space comprising an inlet conduit arranged in intimate heat transferring relation to said body of oil.

12. In combination, a tank for oil immersed electrical apparatus, a body of oil in said tank for dissipating the heat from said electrical apparatus to said tank, said tank having an air space therein above the level of said oil, an outlet member providing a permanently free path for the flow of air from said air space to atmosphere, an inlet conduit arranged so that substantially the whole length thereof is in intimate heat transferring relation to said body of oil and providing a permanently free passageway for the flow of air

from atmosphere to said air space at a point thereof remote from said outlet member.

13. In combination, a casing, a quantity of insulating liquid partially filling said casing, an outlet conduit extending through said casing above the level of said liquid, an inlet conduit extending from above the level of said liquid through said liquid and through said casing to the outside thereof near the bottom of said casing.

14. In combination, a casing, a quantity of insulating liquid partially filling said casing, an outlet conduit in said casing above the level of said liquid, an inlet conduit extending from a point above the level of said liquid through said casing to a point external thereof near the bottom of

said casing, and means for supporting said inlet conduit in heat transferring relation to said liquid.

15. In combination, a casing, a quantity of liquid partially filling said casing, said casing having a space above the level of said liquid, an outlet member providing a permanently free path from said space to the outside of said casing, an inlet conduit arranged so that substantially the whole length thereof is in intimate heat transferring relation to said liquid and providing a permanently free passageway from a point external to said casing to said space at a point thereof spaced from said outlet member.

LOUIS C. NICHOLS.
